REFRIGERATED DISPLAY CASE

Arthur Perez and Roger W. Barr, Niles, Mich., assignors to Clark Equipment Company, a corporation of Michigan

Filed Dec. 30, 1963. Ser. No. 77,975

Term of patent 14 years

(Cl. D80—11)

FIG. 1

The dominant features of the design reside in the portions shown in full lines.

We claim:

The ornamental design for refrigerated display case, as shown and described.
